(57) **CLAIM**

The ornamental design for a tick removal tool, as shown and described.

DESCRIPTION

FIG. 1 is a top-rear-right perspective view of a tick removal tool showing my new design;

FIG. 2 is a bottom-rear-right perspective view thereof;

FIG. 3 is a top plan view thereof;

FIG. 4 is a bottom plan view thereof;

FIG. 5 is a right-side elevational view thereof;

FIG. 6 is a front elevational view thereof; and,

FIG. 7 is a rear elevational view thereof.
